UNITED STATES PATENT OFFICE.

RAYMOND W. DULL, OF LA GRANGE, ILLINOIS, ASSIGNOR TO LINK BELT COMPANY, OF CHICAGO, ILLINOIS, A CORPORATION OF ILLINOIS.

LINK FOR CHAIN-BELTS.

1,396,031.

Specification of Letters Patent.

Patented Nov. 8, 1921.

Application filed March 22, 1920. Serial No. 367,655.

To all whom it may concern:

Be it known that I, RAYMOND W. DULL, a citizen of the United States, residing at La Grange, in the county of Cook and State 5 of Illinois, have invented a certain new and useful Improvement in Links for Chain-Belts, of which the following is a specification.

My invention relates to integral links for 10 chain belts formed from sheet metal of substantially uniform thickness.

Some of the objects of my invention are to provide a wide, supporting base for the hook; substantially tubular, closely fitting, 15 interlocking pintle and hook ends; to form such pintle and hook ends so that the edges of their parts may be on the upper side of the link; and to so form the end forming parts as to diminish the waste of material.

20 Other objects and advantages not herein necessary to mention will be found characteristics of my invention.

It will be understood that I do not wish to be limited to the particular proportions 25 of parts here shown as they may be greatly varied without departing from the spirit of my invention. The hook end is shown in the preferred form but it can be made in any one of a variety of ways.

30 The invention is illustrated in the accompanying drawings, wherein:

Figure 1 is a view of a blank;

Fig. 2 is a plan view of a complete link made from such blank;

35 Fig. 3 is a side elevation of a chain section made from such links.

Like parts are indicated by the same letters in all the figures.

40 A, A are side bars on opposite sides of the opening B. C and D are end bars; E and F, portions which are intended to be cut and upwardly and outwardly bent to form parts of the two ends and G is a hook portion. If a short link is desired, the hole

45 B can be suppressed and if desired, the length of the projection F could more nearly equal the depth of the space between the two free ends of the side bars A, A so that successive links could be cut

50 from a sheet of metal with a minimum waste of material. This latter is one of the important features of this invention.

It will of course be observed that some of the features of my invention can be obtained without using the others.

55

Claims:

1. An integral single thickness sheet metal chain link comprising two side and two end bars and two substantially tubular ends, the pintle end having an external diameter 60 approximately the same as the internal diameter of the hook end, both ends projecting above and below the body and consisting, the pintle end of one end bar and two side bars projecting beyond the end bar and a 65 part which projects from the inner edge of the side bar bent out of line with the link body and toward each other so as to have their opposed ends on the same side of the link body.

70 2. An integral single thickness sheet metal chain link comprising two side and two end bars and two substantially tubular ends, the pintle end having an external diameter approximately the same as the internal diameter of the hook end, the pintle end consisting of one end bar and two side bars 75 projecting beyond the end bar and a part which projects from the inner edge of the side bar bent out of line with the link body 80 and toward each other so as to have their opposed ends on the same side of the link body.

3. An integral single thickness sheet metal chain link comprising two side and two end 85 bars and two substantially tubular ends, the pintle end having an external diameter approximately the same as the internal diameter of the hook end, both ends projecting above and below the body and the pintle 90 end consisting of one end bar and two side bars projecting beyond the end bar and a part which projects from the inner edge of the side bar bent out of line with the link body 95 and toward each other so as to have their opposed ends on the same side of the link body, the hook end consisting of the end bar and two parts projecting therefrom in opposite directions, said parts being curved out of alignment with the link body 100 and toward each other.

4. An integral single thickness sheet metal chain link comprising two side and two end bars and two substantially tubular ends, the

5   pintle end having an external diameter approximately the same as the internal diameter of the hook end, the pintle end consisting of one end bar and two side bars projecting beyond the end bar and a part which projects from the inner edge of the side bar bent out of line with the link body and toward each other so as to have their opposed ends on the same side of the link body, the hook end consisting of the side bar and two parts projecting therefrom in opposite directions, said parts being curved out of alinement with the link body and toward each other.

10   15   5. An integral single thickness sheet metal chain link comprising two side and two end bars and two substantially tubular ends, the pintle end having an external diameter approximately the same as the internal diameter of the hook end, both ends projecting above and below the body consisting, the pintle end of one end bar and two side bars projecting beyond the end bar, and a part which projects from the inner edge of the side bar, bent out of line with the link body and toward each other so that their opposed ends are adjacent each other.

20   30   6. An integral single thickness sheet metal chain link comprising two side and two end bars and two substantially tubular ends, the pintle end having an external diameter approximately the same as the internal diameter of the hook end, the pintle end consisting of one end bar and two side bars projecting beyond the end bar and a part which projects from the inner edge of the side bar, bent out of line with the link body and toward each other.

25   35   35. An integral single thickness sheet metal chain link comprising two side and two end bars and two substantially tubular ends, the pintle end having an external diameter approximately the same as the internal diameter of the hook end, the pintle end consisting of one end bar and two side bars projecting beyond the end bar and a part which projects from the inner edge of the side bar, bent out of line with the link body and toward each other.

bar, bent out of line with the link body and toward each other so that their opposed ends are adjacent each other.

7. An integral single thickness sheet metal 40 chain link comprising two side and two end bars and two substantially tubular ends, the pintle end having an external diameter approximately the same as the internal diameter of the hook end, both ends projecting above and below the body and the pintle end consisting of one end bar and two side bars projecting beyond the end bar and a part which projects from the inner edge of the side bar, the hook end consisting of the 45 end bar and two parts projecting therefrom in opposite directions, said parts being curved out of alinement with the link body and toward each other.

8. An integral single thickness sheet metal 50 chain link comprising two side and two end bars and two substantially tubular ends, the pintle end having an external diameter approximately the same as the internal diameter of the hook end, the pintle end consisting of one end bar and two side bars projecting beyond the end bar and a part which projects from the inner edge of the side bar, the hook end consisting of the 55 side bar and two parts projecting therefrom in opposite directions, said parts being curved out of alinement with the link body and toward each other.

In testimony whereof, I affix my signature this 16th day of March, 1920.

RAYMOND W. DULL.
